UNITED STATES PATENT OFFICE.

HENRY S. HALE, OF PHILADELPHIA, PENNSYLVANIA.

DESIGN FOR A HINGE-ARM FOR CAR-SEAT BACKS.

SPECIFICATION forming part of Design No. 33,339, dated October 9, 1900.

Application filed July 22, 1899. Serial No. 724,871. Term of patent 14 years.

To all whom it may concern:

Be it known that I, HENRY S. HALE, of the city and county of Philadelphia, State of Pennsylvania, have invented a new and original Design for a Hinge-Arm for Car-Seat Backs, of which the following is a specification.

My design for a hinge-arm for car-seat backs is shown in the accompanying drawings, in which—

10 Figure 1 is an elevation of my hinge-arm. Fig. 2 is a plan view of same, and Fig. 3 is an end elevation of same.

The hinge-arm comprises a bracket portion A, extended at the free end and contracted at 15 the forward end. It is also open in structure and curved in plan. The extended end of the bracket is shown at B and the contracted end at C. D is the open-work. The

curvature in plan is shown at E. Extending from the contracted end of the bracket portion A is an oblique arm portion M, comprising two parallel oblique bars F F. The lower ends of these bars are shown as crossing each other at G and terminating in perforated portions H H.

Having now described my design, what I claim as new, and desire to secure by Letters Patent, is—

20 The design for a car-seat-back hinge-arm substantially as herein described and shown. 25

In testimony of which invention I have hereunto set my hand.

HENRY S. HALE.
